US00D716307S

(12) **United States Design Patent**
Paufler et al.

(10) **Patent No.:** **US D716,307 S**
(45) **Date of Patent:** **** Oct. 28, 2014**

(54) **PORTABLE TERMINAL**

(71) Applicant: **Datalogic IP Tech S.r.l.**, Lippo di Calderara di Reno (IT)

(72) Inventors: **David Paufler**, Bologna (IT); **Bin Li**, Shenzhen (CN)

(73) Assignee: **Datalogic IP Tech S.r.l.**, Lippo di Calderara di Reno (BO) (IT)

(**) Term: **14 Years**

(21) Appl. No.: **29/472,543**

(22) Filed: **Nov. 13, 2013**

(30) **Foreign Application Priority Data**

May 16, 2013 (EM) 002238741
Oct. 24, 2013 (EM) 002332858

(51) **LOC (10) Cl.** **14-02**

(52) **U.S. Cl.**

USPC **D14/426**; D14/429

(58) **Field of Classification Search**

USPC ..... D14/420, 426-430, 453, 346, 341, 347, D14/412, 138; D13/107, 184; 358/473; 235/462.43, 462.45, 462.47, 462.48, 235/462.44, 462.46, 487, 472.01, 472.02, 235/145 A, 145 R; D10/78; 324/426; D3/273; 710/73; D18/7; 361/679; 382/313, 321; 455/575.1, 561, 572; 345/156, 168, 169, 172, 173, 87

See application file for complete search history.

(57) **CLAIM**

We claim the ornamental design for a portable terminal, as shown and described.

DESCRIPTION

FIG. 1 is a perspective front view of a portable terminal according to the present invention.

FIG. 2 is a front view of the portable terminal of FIG. 1.

FIG. 3 is a rear view of the portable terminal of FIG. 1.

FIG. 4 is a left side view of the portable terminal of FIG. 1.

FIG. 5 is a right side view of the portable terminal of FIG. 1.

FIG. 6 is a top view of the portable terminal of FIG. 1; and,

FIG. 7 is a bottom view of the portable terminal of FIG. 1.

Broken lines and unshaded portions contained within broken lines are not claimed.

1 Claim, 7 Drawing Sheets
